PILE FABRIC WITH A THROUGH-TO-THE-BACK BIND

Walter M. Ryan, Worcester, Mass., assignor to
 M. J. Wittall Associates, Inc., Worcester, Mass.,
 a corporation of Massachusetts

Application February 20, 1952, Serial No. 272,553

3 Claims. (Cl. 139—403)

1

The present invention relates to textile pile fabrics and more particularly to textile structures adaptable for rug and carpet manufacture.

The principal object of this invention is to provide a novel and improved pile fabric having a through-to-the-back bind, affording a strong textile structure for the rug and carpet manufacturing art.

In the accompanying drawings forming part of this specification, similar characters of reference indicate corresponding parts in all the views.

Fig. 1 is a diagrammatic warpwise view showing the weave structure effected in alternate courses of the fabric in accordance with the teachings of this invention.

Fig. 2 is a similar view showing the weave structure made in the intermediate courses of said fabric.

Fig. 3 is a similar view showing the composite weave in adjacent courses of the fabric.

Fig. 4 is a diagrammatic weftwise view of the said fabric. The courses are here indicated.

Fig. 5 shows a top view of the pile fabric made pursuant to this invention.

In the drawings, in each warp course of the fabric illustrated, there are warp stuffer, one pile yarn and a pair of warp yarns to form the binding chain. The alternate courses are marked "A" and the courses intermediate these are indicated as "B." In the courses "A," the warp stuffer yarns are denoted by the numeral 25, the pile yarn is indicated by the numeral 26 and the chain yarns are designated respectively as 27 and 27'. In the courses "B," the stuffer yarns are indicated by the numeral 35, the pile yarn is 36 and the chain yarns are 37 and 37' respectively. A web 30 is formed of the stuffer yarns 25, 35, incorporating what shall be called the upper wefts indicated by the odd numerals from 1 to 17, to make such web. Intermediate each two upper wefts and below the web 30, but above the pile yarns 26, 36, there is positioned a weft. These wefts, herein called the lower wefts are denoted by the even numbers 2 to 18. The binding yarns 27, 27', and 37, 37', form chain engaging the upper sides of the upper wefts and the undersides of the lower wefts in a manner to be described. Loops 29, 29', 29'', 29''' are raised in each pile warp 26 to extend through the web 30 and above its upper surface. Loops 39, 39', 39'', 39''' are likewise raised from the pile warps 36. The position of said pile loops with respect to each other and their relation with the other components, will be described.

2

In the web 30, the stuffer yarns 25 are over alternate upper wefts and under the other upper wefts, while the stuffer yarns 35 are under those upper wefts the yarns 25 are over, and over those upper wefts the said yarns 25 are under.

Each of the pile loops of the series 29 and 39, have through them two adjacent upper wefts and also the lower weft which is intermediate such pair of upper wefts. For instance, the pile loop 29' in Fig. 1, has through it the wefts 5, 6 and 7.

In each pile yarn, two successive loops have through them respectively, successive pairs of upper wefts and one lower weft respectively; the lower wefts thus associated with two successive loops respectively, are in alternate relation among the lower wefts. The lower weft intermediate such two lower wefts, is above such pile yarn, between said successive loops. For instance, the two successive loops 29' and 29'' in Fig. 1, have through them the wefts 5, 6 and 7 through one, and 9, 10 and 11 through the other, while weft 8 is above the pile yarn 26, between such successive pile loops.

25 In one direction warpwise, one chain yarn in each of the courses, is under all lower wefts which are between successive loops in the pile yarn in the course of the chain yarn dealt with, and over all those upper wefts first nearest to said lower wefts which are between the successive loops. In the same direction warpwise, the second chain yarn in each course, is under all the lower wefts lying through the loops in said pile yarn in its course, and over the other upper wefts which are through said loops. For instance, in the direction from left to right in Fig. 1, the chain yarn 27 is under the lower wefts 4, 8, 12, and over the upper wefts 5, 9, 13. In the same direction, the associated chain yarn 27' is under the lower wefts 2, 6, 10, and over the upper wefts 3, 7, 11.

The loops in adjacent courses are in staggered overlapping relation because the lower wefts which are through the loops in alternate courses, are those which are between the loops in the remaining courses. For instance, the lower wefts 2, 6, 10, which are through the pile loops of the series 29, are between successive pile loops of the series 39.

50 In each course "A" and "B," the loops raised from the pile yarn therealong, are preferably between the stuffer warp and the chain yarn in the course. The pile yarns may all be of one color, or of different colors as may be desired.

55 Also, the loops may be cut as is known in the art. The pertinent advantage of the construction

in pile fabrics herein set forth, is that pile yarn goes under the lower weft, locking same in place and thereby effecting a strong bind, and a very sturdy structure is gained by the included web 30 formed of the stuffer interwoven with the upper weft.

Having described the structure of my new and improved pile fabrics, I desire that the following be protected by Letters Patent, and therefore, I claim:

1. In a textile fabric of the character described, warp yarns in adjacent courses; the warp yarns in each course comprising stuffer yarn, a pile yarn and two chain yarns, and upper and lower wefts positioned across the warp yarns; the lower wefts being intermediate the upper wefts respectively; the stuffer yarns and the upper wefts forming a web wherein the stuffer yarns in alternate courses are over alternate upper wefts and under the remaining upper wefts and wherein the remaining stuffer yarns are under those upper wefts said alternate stuffer yarns are over; and over those upper wefts said alternate stuffer yarns are under the pile yarns being formed with successive loops extending above said web; the loops in adjacent courses being in staggered relation and each loop having through it two adjacent upper wefts and the lower weft which is intermediate such pair of upper wefts; any two successive loops in all the courses, having through them successive pairs of upper wefts respectively; the lower wefts through successive loops, being alternate lower wefts; the lower weft intermediate such alternate lower wefts, being between successive loops; the lower wefts which are through the loops in alternate courses, being those which are between the loops in the remain-

ing courses respectively; one chain yarn in each course, in one direction warpwise, being under all the lower wefts which are between successive loops in the pile yarn in the course of said chain yarn and over all those upper wefts first nearest to said lower wefts between successive loops, and the second chain yarn in each course, in the same direction warpwise, being under all the lower wefts lying through the loops in the pile yarn in the course of said chain yarn and over all those upper wefts first nearest to said latter lower wefts.

2. A textile fabric as defined in claim 1, wherein the loops formed in any pile yarn are between the stuffer warp and the chain yarns in the course of said pile yarn.

3. A textile fabric of the character described, comprising a web composed of warp yarns interwoven with wefts, lower wefts below the web, warp pile yarns of which, alternate ones lie under alternate lower wefts and the intervening ones lie under the intervening lower wefts; said warp pile yarns being formed with successive loops extending through and above the said web; one lower weft lying between every pair of successive loops and warp chain yarns binding the wefts of the web with the lower wefts.

WALTER M. RYAN.
